MECHANISM FOR OPERATING SWITCHES

Stanley H. Durbin, Brooklyn, N. Y., assignor to
 E. W. Bliss Company, Brooklyn, N. Y., a corporation of Delaware

Application October 28, 1941, Serial No. 416,802

3 Claims. (Cl. 200—83)

This invention relates to improvements in mechanisms for operating switches and more particularly to mechanisms adapted to utilize air pressure as the medium for controlling the movements of a movable actuating member of a switch.

The present invention is particularly useful in the operation of electric switches in which an electric circuit may be made, broken, shifted or otherwise varied by a very slight movement of a switch actuating member such as a plunger.

An important object of this invention is the provision of a switch operating mechanism which will respond to relatively slight changes in air pressure.

Another object of this invention is the provision of a switch-operating mechanism which, while fully responsive to sustained pressure changes, nevertheless, is not operatively responsive to momentary pressure changes.

Another object of this invention is the provision of a switch operating mechanism which may easily be adjusted to respond to air pressure changes.

Still another object of this invention is the provision of a switch operating mechanism which is simple in structure and capable of long and constant use without requiring repairs or replacement of parts.

These and other objects and advantages may be derived from the present invention of which, for purposes of illustration, a preferred embodiment is disclosed in the accompanying drawing, in which—

Figure 1 is a central sectional view of a preferred embodiment of the invention, arbitrarily positioned with an air drum and air connections at the top and the electric switch and electric connections at the bottom:

Fig. 2 is a plan view of the embodiment, looking down upon the air drum; and

Fig. 3 is a view looking up to the portion housing the electric switch and connections, the housing being partly broken away to show the switch mounting.

The mechanism is built up about a rigid base plate 11, upon the under side of which is adjustably mounted an electric switch 12 having an actuating plunger 13 extending through an aperture 14 in said base plate, and upon the upper side of which is secured, by means of bolts 15a, an air drum 15 having a diaphragm 16, preferably in the form of a thin metal disc which is positioned adjacent the free end of the plunger 13 and adapted, when slightly flexed, to operate

the switch 12 by moving the said plunger downwardly against the force of a spring (not shown) which coacts with said plunger to hold it yieldably in its uppermost or inoperative position.

The substantially closed upper side 17 of the drum 15 has an outwardly extending boss 18 through which is formed an air passage 19, threaded toward its outer end as at 20 to afford means for connecting an air line thereto, and having at its inner end an aperture 21, preferably of reduced diameter, affording passage for air from such an air line, into the drum 15.

In mounting the drum 15 upon the base plate 11, an annular spacing gasket 22 of suitable thickness is placed between the diaphragm 16 and the base plate to afford space therebetween for the flexing of the diaphragm to an extent somewhat more than sufficient to enable the latter to operate the switch; and an annular sealing gasket 23 of suitable sealing material is placed between the diaphragm 16 and the adjacent bottom surface of the body of the drum 15 to provide an air-tight connection therebetween. The bolts 15a preferably should be tightened sufficiently to prevent slippage of the diaphragm and said gaskets relatively to the base plate and drum and relatively to each other.

The switch 12 is preferably so mounted that it may readily be adjusted to a proper operating relationship with respect to the diaphragm 16. To this purpose, the switch may be mounted within a rigid yoke 24 by means of screws 25, and the yoke may be carried upon adjusting screws 26 extending through each end of said yoke, thence through compression coil springs 27, and threaded into holes 28, provided therefor in the base plate 11. The said springs normally urge the yoke 24 into coaction with the heads of the adjusting screws 26 and, by screwing the latter in or out as necessary, the switch 12 may be adjusted to the precise position in which the plunger 13 thereof will coact properly with the diaphragm 16 during flexing of the latter to operate said switch. Once this adjustment is attained, the frictional engagement of the threaded portions of the adjusting screws 26 within the holes 28 may suffice to maintain the adjustment. An additional assurance of the maintenance of this adjustment may be derived by the use of lock washers 29 disposed on the adjusting screws 26 between the heads of the latter and the yoke 24.

The switch is preferably enclosed by a cover 30, suitably fastened to the base plate 11 as by cover screws 31. The cover, with the base plate, forms an enclosure 32 for said switch and a

threaded opening 33 is provided in the base plate to afford means for connecting thereto an electric conduit from within which electric wires (conduit and wires not shown) may pass into said enclosure for connection to terminals 34 of the switch. The cover, of course, may be easily removed to permit adjustment of the switch and connection of wires thereto and the interior of the said enclosure may be suitably insulated.

In practice, the mechanism may be connected, at the threaded portion 20 of the passage 19, to an air line, the pressure within which is desired to operate said mechanism. When so connected, the switch may be employed to control a circuit in apparatus adapted to restore air pressure in said air line if such pressure has increased or decreased beyond permissible limits; or said switch may be used to open or close or otherwise modify a circuit adapted to control apparatus which actuates or which may prevent actuation of a machine in which the mechanism is employed; or it may be used both to control the restoration of pressure in said air line and to control the operation of such a machine while such restoration of pressure is in progress. The mechanism may also be put to other uses than those mentioned herein.

The disc selected for use as the diaphragm 16, ordinarily, should be of such thickness and other characteristics that it will flex to the proper extent, under the pressure and pressure variations to which it may be subjected in the use in which it is to be employed, to move the plunger 13 sufficiently to operate the switch 12.

In one mode of operation, it may be assumed that the air pressure normally present in the air line to which the device is connected and, consequently, present within the drum 15 either will not flex the diaphragm 16 materially or will flex it only slightly downwardly as viewed in Fig. 1. Upon the establishment of such normal air pressure within the drum 15, the position of the switch 12 may be adjusted by suitable turning of the adjusting screws 26 to bring the end of the plunger 13 (then yieldably held in its inoperative or normal position) into intimate juxtaposition to the center of said diaphragm. Then, upon any increase of pressure in the drum, beyond permissible or predetermined limits the diaphragm will flex downwardly or the flexing thereof will increase to cause it to engage and press the plunger 13 downwardly to an extent sufficient to operate the switch 12. When the air pressure drops back to normal, the diaphragm unflexes to permit the plunger 13 to move outwardly to its inoperative position. The effective movement of the plunger in such a switch may be very slight as, for example, 0.001" so that a relatively slight pressure variation will cause sufficient flexing of the diaphragm to operate the switch.

If it is desired to have the switch 12 operate as a result of a decrease in air pressure, the characteristics of the diaphragm 16, preferably, should be such that normal air pressure will cause material downward flexing of the diaphragm and the adjustment of the position of the switch should then bring the end of the plunger 13 in engagement with the center of the diaphragm with the plunger in depressed position, which, in the switch employed in this arrangement may be said to be its inoperative position. Any drop in air pressure would then diminish the flexing of the diaphragm and permit the plunger to move upwardly under the force of its actuating spring to

operate the switch. Other modes of operation of the mechanism may also be arranged.

Although it is suggested that the characteristics of the diaphragm 16 may be selected with particular reference to the pressures involved, the device, with a selected diaphragm, may nevertheless be employed to respond to pressures extending over a relatively wide range in view of the means for the substantial adjustment provided in the switch mounting.

The size of the aperture 21 has a material effect upon the operation of the device. By making said aperture relatively small in cross-sectional area, momentary pressure variations in the air line to which the device is connected, produce little or no variation in the pressure within the drum 15 and, hence, the switch is operated only by somewhat sustained pressure variations. On the other hand, said aperture may be made relatively large, so that even momentary pressure variations in the air line would be reflected instantly within the said drum and the switch would respond either to momentary or sustained pressure variations. The determination of the size of said aperture depends, of course, upon the manner in which the switch is desired to function in the particular machine in which it is employed.

It will be understood that the inventive concept may be employed in various ways other than those disclosed herein without departing from the invention as defined in the accompanying claims.

What I claim is:

1. An operating mechanism for a switch having a reciprocable actuating member, said mechanism comprising a mounting piece, a rigid air drum fixed upon said mounting piece, means for connecting the interior of said drum with a controlling air source located exteriorly thereof, a diaphragm airtightly secured upon said drum to form, with the latter, an air chamber, and means for holding such a switch upon said mounting piece with its actuating member in operating relationship relatively to said diaphragm whereby said switch may be actuated by movement of its actuating member in response to flexing of the diaphragm caused by air pressure variations within said air chamber, the said switch-holding means being adjustable whereby to permit adjustment of the position of the switch relatively to the diaphragm, the said switch-holding means comprising a rigid member adapted for carrying said switch, a screw coacting with said member and said mounting piece to positively move said member and the switch carried thereby toward said diaphragm, and resilient means coacting with said rigid member and opposing movement of said switch toward said diaphragm.

2. In combination, an electric switch having an actuating plunger, a mounting plate having an opening extending therethrough, adjustable switch-holding means adapted to hold said switch upon one side of said plate with the said plunger extending through said opening, a diaphragm mounted upon the other side of said plate with a flexible portion thereof disposed adjacent the free end of said plunger, a rigid air drum fixed upon said plate in air-tight connection with said diaphragm and forming, with the latter, an air chamber, and means for connecting the interior of said chamber with a separate controlling air source, the said diaphragm being adapted to flex in response to variations in air pressure in said chamber and to coat with said plunger whereby

to move the latter and operate the switch, and the switch-holding means comprising a rigid member upon which the switch is fixed, and two or more screws coacting with different portions of said member and threaded into holes in said plate, the said screws being restrained against longitudinal movement relatively to said member and being adapted, by screwing them inwardly and outwardly relatively to said plate, to effect adjustment of the position of the switch relatively to the diaphragm.

3. In combination, an electric switch having an actuating plunger, a mounting plate having an opening extending therethrough, adjustable switch-holding means adapted to hold said switch upon one side of said plate with the said plunger extending through said opening, a diaphragm mounted upon the other side of said plate with a flexible portion thereof disposed adjacent the free end of said plunger, a rigid air drum fixed upon said plate in air-tight connection with said

diaphragm and forming, with the latter, an air chamber, and means for connecting the interior of said chamber with a separate controlling air source, the said diaphragm being adapted to flex in response to variations in air pressure in said chamber and to coact with said plunger whereby to move the latter and operate the switch, and the switch-holding means comprising a rigid member upon which the switch is fixed, two or more headed screws extending through said member at different points thereon and threaded into holes in said plate, and compression springs extending about the shanks of said screws, the ends of the springs pressing against said plate and said rigid member whereby to hold the latter against the screw heads and constrain the said member and the switch thereon to move toward or away from the diaphragm as the said screws are turned inwardly or outwardly with respect to the mounting plate.

STANLEY H. DURBIN.
